CLAIM

The ornamental design for a sand trap grooming rake, as shown and described.

DESCRIPTION

FIG. 1 is a front, top and side perspective view of the sand trap grooming rake showing my new design; FIG. 2 is an end elevational view thereof, the end opposite being a mirror image of the end shown in FIG. 2; FIG. 3 is a front elevational view thereof, the rear being a mirror image of the front shown in FIG. 3; FIG. 4 is a top plan view thereof; and, FIG. 5 is a bottom plan view thereof. The handle being partially shown for the sake of convenience of illustration, the undisclosed portion of the handle being plain and unornamented and the top end being conventionally hemispherical.

FIG. 1

FIG. 2

FIG. 3

FIG. 4

FIG. 5
